HINGE

Stephen J. Palinkos, South Norwalk, Conn.

Application December 13, 1934, Serial No. 757,381

1 Claim. (Cl. 16—181)

This invention appertains to new and useful improvements in hinges and more particularly to a hinge of the spring return type.

The principle object of the present invention is 5 to provide a hinge of a special construction, adapted particularly for use in conjunction with a screen door and other closures which are seasonally or periodically removed from use.

Other important objects and advantages of the 10 invention will become apparent to the reader of the following specification.

In the drawings:

Figure 1 represents a fragmentary front elevational view showing a screen door and frame therefor with a novel hinge employed therewith.

Figure 2 represents a fragmentary front elevational view of a door hinge showing the anchor plate.

Figure 3 represents an outside elevational view 20 of the screen door provided with the novel hinge.

Figure 4 represents a perspective view of the anchor plate.

Figure 5 represents an outside elevational view 25 of the hinge assembled.

Figure 6 represents a top plan view of the novel hinge with the door frame in section.

Figure 7 represents an elevational view of one 30 of the hinge plates.

Figure 8 represents a sectional view taken substantially on the line 8—8 of Figure 7.

Figure 9 represents an outside elevational view 35 of the other hinge plate.

Figure 10 represents a sectional view taken substantially on line 10—10 of Figure 9.

Figure 11 represents an end elevational view 40 of the spring.

Referring to the drawings wherein like numerals designate like parts, it can be seen in Figure 1 that numeral 5 represents a screen door while numeral 6 represents the frame therefor.

While referring to Figures 5 to 10 inclusive it can be seen that the hinge proper is made up of the hinge plate A and the hinge plate B, the hinge plate A being provided with top and bottom flanges 7—7 each provided with an inwardly turned lug 8. The plate A is also provided with opening 9 for the reception of securing means whereby the plate is secured to the door 5.

The hinge plate B includes a slotted barrel 10 50 running longitudinally thereof and provided with openings 11 in the ends thereof. This plate B

is also provided with an opening 12 the upper and lower ends of the barrel 10 are provided with inwardly disposed stop lugs 8 at the slotted portions thereof. The flanges 7—7 are connected with the barrel 10 by a pintle extending through openings in the flanges and the barrel 10.

Figures 2 and 4 show the anchor plate which consists of a plate member 13 having guides 14—14 at the upper and lower ends thereof and securing elements 15 in the form of screws extending through the plate and securing the plate to the frame 6.

Anchor plate 13 is provided with an opening 16 with which the opening 12 in the hinge section B is to be registered.

It can now be seen, that the coil 17 of the spring 18 is properly bent in the barrel 10 so that the ends 19 and 20 extend outwardly through the upper and lower ends of the barrel 10.

The end portion 19 bears against the plate A, 20 while the end 20 of the spring bears against the plate B with the end thereof extending through the registering opening 12—16 thus securing the plate B against sliding action on the plate 13. 25 Thus, the assembly consisting of the plates A—B is anchored to the anchor plate 13 and when it is desired that the door be removed, the end 20 of the spring 18 can then be prised from the opening 12—16 after which the plate B can be conveniently slid off of the anchor plate 13.

While the foregoing specification sets forth the invention in specific terms, it is to be understood that numerous changes in the shape, size, and material may be resorted to without departing from the spirit and scope of the invention as 35 claimed hereinafter.

Having thus described the invention, what is claimed as new is:

In combination, a hinge consisting of a pair of leaves and provided with means swingably connecting the same together, a spring for retaining the sections in closed position, an anchor plate, guide structures on the anchor plate for receiving one of the hinge sections, said anchor plate and said mentioned section of the hinge being provided with registering openings, said spring being provided with an extension for engagement into the openings when said openings are registering.

STEPHEN J. PALINKOS. 50
